GAME COUNTER

Louis E. Baltzley, Glen Ridge, N. J.

Application July 17, 1930. Serial No. 468,607

3 Claims. (Cl. 273—148)

This invention relates to game counters, in the nature of poker chips and the like, and the objects of the invention are to provide an article of this type, which can be readily handled and picked up off a table or other flat surface, which can be readily stacked, which will be attractive in appearance, which will hold its color or other ornamentation or markings and which can be produced inexpensively in various styles suitable for 10 different games.

These objects are attained in the construction herein disclosed by the novel features herein-after described and broadly claimed.

The drawings accompanying and forming part 15 of the specification illustrate several practical embodiments of the invention, it being understood that the structure may be modified to suit varying requirements without departure from the true spirit and broad scope of the invention.

20 Fig. 1 is a perspective view illustrating one of the counters or chips and showing how the same automatically tilts up into the grasp of the fingers upon pressure on one edge of the same; Fig. 2 is a side view illustrating how the fingers 25 come together through the opening in the counter to securely hold it even with light pressure; Fig. 3 is an enlarged cross-sectional view of the counter as on the line 3—3 of Fig. 1. Fig. 4 is a perspective view illustrating a modification; 30 Fig. 5 is a cross-sectional detail of another modification; Fig. 6 is a plan view of a further modification.

The counter first illustrated is in the form of a disc 5 having a central opening 6 and provided 35 with circularly spaced segments 7, 8, raised or embossed in alternate order on opposite faces of the same between the rim and centrally perforated portions.

In the construction shown, the raised segments 40 are produced by embossing and hence depressions 9 of corresponding segmental outline are left in each face of the counter opposite the segments raised on the other face of the counter. These 45 segmental depressions form seats for coloring matter or other markings, between the raised portions, which latter operate as guards protecting such marks from wear by contact between the counters or with the table or supporting surface.

50 The raised portions are shown as having relatively sharp outer edges 10 to provide angular shoulders, which will serve as fulcrums for the up-tilting of the counter when pressure is exerted on the rim of the disc as in the line of the arrow 55 11 in Fig. 3. By such up-tilting, the disc is brought

into the easy grasp of the fingers and the fingers then naturally hold the counter through the center opening therein as in Fig. 2, this being a particularly easy but secure way of gripping and handling the article.

60 By embossing alternate areas at opposite sides of the disc, the final overall thickness of the disc may be substantially tripled, as in the illustration, to form fulcrum shoulders of ample height, from relatively thin stock material. The 65 embossing action may be either a punch or a molding operation, depending on the character of the material from which the counters are made. The coloring matter may fill up the depressions substantially flush with the original surface of 70 the disc, as indicated, where 12 designates a body of enamel or other coloring matter filled in these seats or depressions.

The counters may be made from flat stock material, so that when the segmental portions are 75 raised from the opposite faces of the same, there will be a thin flat parallel faced rim portion surrounding the abrupt angular fulcrum shoulders at the outer ends of the segments, enabling the counter to be readily tilted whether it be on a 80 hard surface or a softer surface, such as might be provided by a table cover. The segments terminating short of the center disc leave a recessed open portion at the center, which is readily grasped by the fingers when the disc is tilted up 85 by pressure on the outwardly extending leverage portion at the edge of the same.

To better identify the counters when viewed edgewise as in Fig. 3, a groove 13 may be formed 90 about the outer ends of the segments and this groove may be filled with enamel, extending up over the backs or outer edges of the segments as indicated at 14. Also in this view the identifying color is shown as extended up over the side edges of the segments at 15. This construction 95 thus enables the counters to be readily identified when viewed edgewise in a stack. The groove also gives a continuity to the color, which makes the counters more easily identified. The flat rim portion at the edge of the counter may be quite 100 narrow as shown in Fig. 3, so as to cause the disc to tilt upward at quite a sharp angle when pressure is applied to the rim.

Instead of forming perforations entirely 105 through the center of the counter, this central portion may be merely a depression or concavity as indicated at 16 in Fig. 5.

To prevent the counters from rolling too readily, the same may be made of polygonal outline, such as illustrated generally in Fig. 6, wherein 110

one of the counters is shown made with a plurality of angularly related sides 17.

What is claimed is:

- 5 1. A game counter, comprising a disc having depressions in each side and correspondingly raised portions on the opposite sides, said raised portions being spaced inward from the rim of the disc to afford fulcrums for up-tilting the disc when pressure is applied to the rim of the same.
- 10 2. A game counter, comprising a disc having depressions in each side and correspondingly raised portions on the opposite sides, said raised portions being spaced inward from the rim of the

disc to afford fulcrums for up-tilting the disc when pressure is applied to the rim of the same, and said disc having an opening therethrough at the center of the disc beyond the inner ends of the oppositely raised portions enabling the fingers to more readily grip the disc when up-tilted by pressure on the rim of the same.

80

3. A game counter, comprising a disc having spaced, raised, segmental portions on opposite faces of the same spaced inward from the rim of the disc and spaced outward from the center of the disc.
